UNITED STATES PATENT OFFICE

1,986,166

PLASTIC MATERIAL DISPENSER

Franz Karl Schneider, Philadelphia, Pa.

Application September 26, 1933, Serial No. 691,032

3 Claims. (Cl. 18—3.5)

My invention relates generally to dispensers, and more particularly to a dispenser which is adaptable to the dispensing of plastic materials.

In a device of this general character, it is desirable to provide a structure which is conveniently portable, readily applicable to corners, crevices and other difficultly accessible places and is, furthermore, flexibly adapted to the dispensing of materials of varying consistency and viscosity.

An object of my invention, generally expressed, is to provide a device for dispensing plastic material.

A more specific object of my invention is to provide a device for dispensing plastic materials to places ordinarily inaccessible to the conventional dispensing devices because of their rigidity of design and construction. The inconvenience of thus applying plastic material to such places is overcome by a feature of my invention in which the stock and the trigger of the device can be rotated about its plunger and cylinder.

A further object of my invention is to provide a dispenser in which the stroke of the plunger can be varied through a wide range, thereby not only controlling within wide limits the quantity of material ejected but also the pressure to be applied to the substance to be ejected.

An additional object of my invention is to provide a means for the easy and quick application of nozzles of differently shaped cross sections in order that the plastic material may be ejected in forms necessary and desirable for varying circumstances.

Still another object of my invention is the ease and cleanliness with which the dispenser can be loaded. To this end the dispenser applies the "suction" generated by the freely moving piston rod and piston.

For the purpose of illustrating my invention I have shown in the accompanying drawing forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

My invention relates to several other novel features of construction and advantage appearing as hereinafter described and claimed in connection with the accompanying drawing in which:

Fig. 1 is a sectional elevation of the dispenser

showing details of its design when completely assembled.

Fig. 2 represents an enlarged sectional plan view of the structure actuating the piston rod.

Figs. 3 and 4 represent two of many types of nozzles that may be attached to the dispenser.

Fig. 5 represents the dispenser in position for receiving a charge of plastic material.

Referring to the drawing in which like reference characters indicate like parts, 1 is a cylinder fabricated of suitable material in which moves tightly the piston 2, suitably ringed with leather or other desirable material 3 and rigidly attached to the piston rod 4. A spring 5 cushions the piston when it is withdrawn to the trigger end of the dispenser. The nozzle end of the cylinder 1 is threadedly engaged to the cap 6 into which can be conveniently inserted the nozzle 7, 8 or 9. The nozzles 7, 8 and 9 are conventional in structure and use and are shown merely to illustrate the flexibility and the range of application of my dispenser.

To the trigger end of the cylinder 1 is threadedly engaged the perforated cap 10. Within the cap 10 is positioned a perforated disc 11 to which the stock 12 is riveted or otherwise securely attached. As a consequence I achieve an important function with my dispenser in enabling the operator to rotate the stock 12 freely without disturbing the position of the nozzle 7, 8 or 9 when applied to a difficultly accessible place. Surrounding the piston rod 4 and lying between the disc 11 and the plate 13 is the compression spring 14 which holds the plate 13 securely against the inner surface of the stock 12 as a fulcrum and permits a limited rotation of the plate 13 against its action about the piston rod 4 as indicated by the curved arrow. The plate 13 is preferably fabricated of hard material, is perforated to receive the piston rod 4 and, when actuated by the trigger 15, seizes the piston rod 4 with a "biting in" grip and forcibly propels the piston rod 4 forward toward the nozzle end of the dispenser. The trigger 15 is a bent lever in which one or more holes 16 and 17 can be drilled for the purpose of varying the ratio of the lever arms and of permitting greater or lesser mechanical advantage, depending upon the viscosity of the plastic material to be ejected.

To the rear surface of the stock 12 is attached the short movable link 18 which is rotatably hinged to the lever 19. A compression spring 20 holds the lever 19 firmly against the piston rod 4 and prevents any retrogressive movement of

the piston rod 4. By means of the catch 21, however, the lever 19 can be securely locked to the stock 12 against the action of the spring 20 in order to facilitate movement inwardly or outwardly of the piston rod 4. The detent 22 positioned on the piston rod 4 limits the movement of the piston rod 4 into the cylinder 1.

To the extreme end of the piston rod 4, adjacent to the stock 12, is threadedly or otherwise engaged the bell-shaped cap 23 which serves as a handle or a rest when the dispenser is in actual use.

The manner in which my device can be utilized becomes obvious when the operation is more fully described. In order to charge the dispenser with plastic material the nozzle 7, 8 or 9 and the cap 6 are readily detached and the cylinder 1 is pressed into the gasket 24 of resilient material surrounding the upturned perforation 25, punched into the shallow plate 26. The plate 26 rests upon the plastic material in a container (not shown). The lever 19 is locked to the stock 12 by the catch 21, the piston rod 4 is withdrawn to the end of its stroke and, by "suction", the plastic material flows into the cylinder 1. With the lever 19 thus securely locked to the stock 12 the piston rod 4 can be moved freely in both directions in the cylinder 1. When the piston rod 4 is pulled out of the cylinder 1 the dispenser can be charged; when the piston rod 4 is pushed into the cylinder 1—under the conditions previously described—the dispenser can be utilized as an ordinary squirt gun. In this procedure the dispenser can be quickly and cleanly charged. The cap 6 and the desired nozzle are then replaced, the lever 19 is unlocked and the dispenser is then in condition for the application of the plastic material. With the trigger 15 set for a desired mechanical advantage, applied force rotates it about its fulcrum 17 and brings its short arm into contact with the plate 13. The sharp, hard edge of the plate 13 "bites" into the piston rod 4 and forcefully propels it forward carrying with it the piston 2 and the plastic material to be ejected through the nozzle 7, 8 or 9. With continued use the piston rod 4 becomes ridged and roughened and accordingly can be more securely seized by the plate 13. After the plate 13 has "bitten" into the piston rod 4 to propel it forward the plate 13 holds the rod 4 securely in a fixed position and prevents any retrogressive movement or recoil of the rod 4.

It is to be further observed that with the lever 19 locked to the stock 12 by means of the catch 21 the piston 4 can move in both directions in the cylinder 1 and thereby make of my device an ordinary squirt gun.

While the construction as shown and described is the preferred embodiment of my device, nevertheless the same may be modified in detail without departing from the spirit and the scope of the invention as defined in the annexed claims.

Having thus described my invention, I claim as new and desire to secure by Letters Patent:

1. In a device for dispensing plastic material a cylinder; a piston therein; a piston rod adapted to be moved freely in a reciprocating manner and in combination with a gripping plate and a compression spring, said gripping plate engaging directly with said piston rod against the action of said compression spring to propel said piston rod forwardly; a trigger to actuate said gripping plate; a link; a lever; a compression spring; and a stock adapted to house said trigger and to rotate continuously within and independently of other connections of it with said cylinder, said link being rotatably attached at one extremity to said stock and rotatably attached at the other extremity to said lever, said lever being perforated to receive said piston rod, and said link, lever and compression spring associated and adapted as a recoil mechanism to prevent retrogressive movement of 20 said piston rod.

2. In a device for dispensing plastic material a cylinder; a piston therein; a piston rod adapted to be moved freely in a reciprocating manner and in combination with a gripping plate and a compression spring, said gripping plate engaging directly with said piston rod against the action of said compression spring to propel said piston rod forwardly; a trigger to actuate said gripping plate; a link; a lever; a compression spring; a nozzle 30 readily attachable to said cylinder; and a stock adapted to house said trigger and to rotate continuously within and independently of other connections of it with said cylinder, said link being rotatably attached at one extremity to said stock 35 and rotatably attached at the other extremity to said lever, said lever being perforated to receive said piston rod, and said link, lever and compression spring associated and adapted as a recoil mechanism to prevent retrogressive movement of 40 said piston rod.

3. In a device for dispensing plastic material a cylinder; a piston therein; a piston rod adapted to be moved freely in a reciprocating manner and in combination with a gripping plate and a compression spring, said gripping plate engaging directly with said piston rod against the action of said compression spring to propel said piston rod forwardly; a trigger to actuate said gripping plate; said trigger consisting of a variable lever adapted to yield a variable mechanical advantage; a link; a lever; a compression spring; a nozzle readily attachable to said cylinder; and a stock adapted to house said trigger and to rotate continuously within and independently of other connections of it with said cylinder, said link being rotatably attached at one extremity to said stock and rotatably attached at the other extremity to said lever, said lever being perforated to receive said piston rod, and said link, lever and compression spring associated and adapted as a recoil mechanism to prevent retrogressive movement of said piston rod.

FRANZ KARL SCHNEIDER.
